Primary Examiner — Susan Moon Lee**CLAIM**

I claim the ornamental design for a pet bowl, as shown and described.

DESCRIPTION

FIG. 1 is a top perspective view of a pet bowl showing our new design;

FIG. 2 is a first side elevation view thereof;

FIG. 3 is a second side elevation view thereof;

FIG. 4 is a third side elevation view thereof;

FIG. 5 is a fourth side elevation view thereof;

FIG. 6 is a top plan view thereof; and,

FIG. 7 is a bottom view thereof.

Broken lines and portions contained within unshaded broken lines are not claimed.

The pet bowl is shaped such that an animal will eat slowly.
